DECORATIVE LIGHT

Arthur Stechbart, Chicago, Ill., assignor to
Matchless Electric Company, Chicago, Ill., a
corporation of Illinois

Application March 16, 1936, Serial No. 69,089

7 Claims. (Cl. 240—10)

This invention relates to ornamental or decorative light devices such as is shown in the prior application of Paul C. Dittman, Serial Number 19,417, filed May 2, 1935, now Patent No. 2,063,153. 5 In devices of this character, the problems of mounting and securing the crystals or solid prismatic bodies of glass is one of the principal problems in the construction of such devices. The intrinsic value of the crystals is such that it is preferable to continue their use much longer than the life of the light bulb utilized to illuminate such devices.

One of the purposes, therefore, of the present invention is to provide in an assembly of this character a novel mounting for the light bulb whereby new light bulbs may be applied to the crystal structure without the necessity of any particular tools or implements. In other words, it is the purpose of the present invention to so construct the light unit that the ultimate purchaser who uses the unit as an ornamental light can, with little or no difficulty, transfer the crystals to a new light source without the aid of special tools or machinery.

It is another purpose of the present invention 25 to provide a novel base structure for mounting the crystals and positioning them with respect to the light source.

A further purpose of the invention is the provision of novel interlocking mounting units 30 whereby a plurality of rows of crystals may be connected together and to a supporting base.

It is a further purpose of the present invention to provide in a device of this character a 35 novel means for connecting a row of crystals, which are substantially diamond shaped in cross section when cut lengthwise thereof, to a supporting base so as to have the crystals arranged radially about a common center.

A further purpose of the invention is to provide 40 a novel center crystal supporting and pointed crystal positioning unit for devices of this character.

Other and more specific objects and advantages of the invention will appear as the description proceeds in connection with the accompanying drawing wherein the preferred form of the invention is shown. It is to be understood, however, that the drawing and description are illustrative only and are not to be taken as limiting the invention except in so far as it is limited by the claims.

In the drawing—

Fig. 1 is a plan view of a decorative light structure embodying the present invention;

Fig. 2 is a sectional view taken on the line 2—2 of Fig. 1;

Fig. 3 is a bottom plan view of the device partly in section;

Fig. 4 is a fragmentary sectional view taken

substantially on the line 4—4 of Figs. 1 and 2; and

Fig. 5 is a fragmentary view showing the manner in which the securing wires are applied.

Referring now in detail to the drawing, the 5 decorative light structure is made up essentially of a light bulb 10, a mounting base 11, a large back row 12 of elongated prismatic glass bodies, a second row 13 of smaller glass bodies similar in shape to the row 12, and a central ornament 10 or crystal 14. In many aspects, the invention is applicable to the combinations where one of the rows 12 or 13 is dispensed with, and obviously the particular type of central ornament 14 is of minor importance. 15

As disclosed in the prior application hereinbefore referred to, the glass bodies which make up the rows 12 and 13 are cut so as to produce elongated pointed crystals that entrap light entering the crystals from one end and cause it to 20 be reflected from at least one face of the crystal before it can be directed outwardly from the crystal. The crystals, as shown, are provided with sixteen faces, and the faces run from the end points substantially to the center along the longitudinal axis of the crystal. The faces, however, 25 are cut in such a fashion that the line adjoining two faces running from one point strikes about the center of a face running from the other point of the crystal. The angles the several faces make 30 with the longitudinal axis of the crystal are approximately 20 degrees so that the angle between two opposite faces of the crystal is substantially 35 40 45 50 55 row 12 so that the crystal may rest firmly in the depression with a securing ring 26 interposed between the several crystals and the base 11. This securing ring 26 is made of a strip of sheet metal and is bent to fit snugly against the top surface of the base 11.

The several crystals making up the row 12 are held in place against the ring 26 in a manner which will be presently described. The ring 26, 10 however, is the sole connection between the base 11 and the crystal structure. This ring is releasably secured to the base 11 by a plurality of tongues 27, 28, and 29 extending from the ring and bent over beneath the lower surface of the 15 base 11. The material of the tongues is preferably made soft enough that it can be readily bent so as to release the tongues from the base 11 and thus permit removal of any crystal structure from the base without any tools or equipment other than would be commonly found in the home.

The replacement of the light bulb 10, therefore, becomes a simple matter since the owner of the crystal structure need only purchase the light 25 bulb equipped with the base 11.

The several crystals making up the row 12 are secured together by means of a wire loop 30 which is threaded through openings in the inner ends of the crystals. The crystals making up the row 30 13 are secured together by a series of wires 31, 32, and 33 which wires are passed between adjacent crystals of the row 12 and are soldered or otherwise secured to the ring 26 as indicated at 34 in Figs. 2 and 4. The loose ring 30 and that 35 ring made up of the parts 31, 32, and 33 are not, however, sufficient to adequately position the several crystals so I provide in conjunction therewith a binding ring 35. This ring 35 has depending fingers 36 which extend between the 40 crystals in the row 13 and hook under the wires 31, 32, and 33 thus to place and position the crystals in the row 13 so that they cannot be dislodged. The ring 35 has its body portion 37 bent substantially to the shape of a frustum of a cone. The ring 35 thus serves as a supporting and spacing device for the crystals in the row 13.

This ring also serves as a supporting and securing means for the central ornament 14. This central ornament, which may be a piece of cut 50 glass, has a conical bottom face 38 adapted to rest against the conical part 37 of the ring 35. The central ornament also has a shoulder at 39, and the ring 35 has a plurality of fingers 40 extending upwardly and hooked over the shoulder 55 39 to fix the central ornament in position. The entire ring 35 is formed of one piece, the fingers 36 being struck out from the material, and the fingers 40 being also formed in this fashion. As shown most clearly in Fig. 1, the fingers 40 are 60 offset between the fingers 36 so that there is no wasted material to speak of.

From the above description, it is believed to be evident that I have provided a simple and effective assembly unit for the several crystals whereby 65 they are held in position so that they cannot be dislodged and yet wherein they are free to move and adjust themselves as they expand and contract when heated or cooled. The mounting in the above fashion also makes it possible to secure 70 the crystals and still leaves plenty of space for air circulation between the crystals and the light bulb. Thus the problem of excessive heat from the light source is eliminated.

Having thus described one specific form of my

invention, what I claim as new and desire to secure by Letters Patent is:

1. A decorative light structure comprising in combination, a light bulb, a light transmitting and display structure comprising a plurality of crystals connected together and encircling said bulb, a base fixed to said bulb, and a mounting ring having means thereon positioning said crystals with respect to each other, said ring and said base having seats therein in which certain of said crystals rest. 5

2. A decorative light structure comprising in combination, a light bulb, a light transmitting and display structure comprising a plurality of crystals connected together and encircling said bulb, a base fixed to said bulb, and a mounting ring having means thereon positioning said crystals with respect to each other, said ring and said base having seats therein in which certain of said crystals rest, and means detachably connecting said ring to said base. 15

3. A decorative light structure comprising in combination, a light bulb, a light transmitting and display structure comprising a plurality of crystals connected together and encircling said bulb, a base fixed to said bulb, a mounting ring having seats for certain of said crystals, means detachably securing said mounting ring to the base, a binding ring holding said crystals against the mounting ring, and a central ornament carried by said binding ring. 20

4. A decorative crystal assembly for detachable mounting upon a light bulb comprising a pair of rigid annular members, annularly arranged crystals held between said members with their inner ends spaced to receive a light bulb therebetween, and means securing said crystals and members together in a unitary annular structure into which a light bulb may be inserted. 25

5. A decorative crystal assembly for detachable mounting upon a light bulb, comprising a pair of rigid annular members, annularly arranged crystals held between said members with their inner ends spaced to receive a light bulb therebetween, means securing said crystals and members together in a unitary annular structure into which a light bulb may be inserted, and one of said members having a center ornament mounted thereon to cover the end of the light bulb. 40

6. A decorative crystal assembly for detachable mounting upon a light bulb, comprising a pair of rigid annular members, annularly arranged crystals held between said members with their inner ends spaced to receive a light bulb therebetween, means securing said crystals and members together in a unitary annular structure into which a light bulb may be inserted, one of said members having a center ornament mounted thereon to cover the end of the light bulb and the other member having attaching means thereon by which it may be mounted on a light bulb. 50

7. A decorative crystal assembly for detachable mounting upon a light bulb, comprising a pair of rigid annular members, annularly arranged elongated pointed crystals forming an annulus with their long axes directed outwardly to provide a multiple-pointed star-shaped assembly, said crystals being held between said members and having their inner ends spaced to receive a light bulb therebetween, and means securing said crystals and members together in a unitary annular structure into which a light bulb may be inserted. 65
